(57) **CLAIM**

The ornamental design for stereoscopic eyewear, as shown and described.

DESCRIPTION

FIG. 1 is a perspective view of stereoscopic eyewear showing the new design;

FIG. 2 is a front elevation view thereof;

FIG. 3 is a right side elevation view thereof, the left side elevation view being a mirror image of the right side elevation view;

FIG. 4 is a rear elevation view thereof;

FIG. 5 is a top view thereof; and,

FIG. 6 is a bottom view thereof.

The broken lines in the Figures show environmental structure and form no part of the claimed design.
